[57] **CLAIM**

The ornamental design for a pneumatic separator, as shown and described.

DESCRIPTION

FIG. 1 is a front elevational view of a pneumatic separator, with the conveyor belt shown in phantom showing my new design;

FIG. 2 is a rear elevational view thereof;

FIG. 3 is an elevational view of the right-hand side of FIG. 1;

FIG. 4 is an elevational view of the left-hand side of FIG. 1;

FIG. 5 is a top plan view thereof;

FIG. 6 is a front perspective view thereof to a somewhat reduced scale with the conveyor belt shown in phantom; and,

FIG. 7 is a rear perspective view thereof to a slightly reduced scale.
